UNITED STATES PATENT OFFICE.

WILLIAM J. LARIMER, OF KANSAS CITY, KANSAS.

OIL-BURNER.

1,072,624.

Specification of Letters Patent.

Patented Sept. 9, 1913.

Application filed November 26, 1912. Serial No. 733,658.

To all whom it may concern:

Be it known that I, WILLIAM J. LARIMER, a citizen of the United States, residing at Kansas City, in the county of Wyandotte and State of Kansas, have invented certain new and useful Improvements in Oil-Burners; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 My invention relates to oil burners, and more particularly to a device for use in furnaces and stoves and wherein oil is vaporized and mixed with a supply of fresh air to produce a combustible fuel vapor; the 20 principal object of the invention being to provide improved details of structure for securing proper vaporization and for spreading flame within the fire bowl of the stove with which the burner is used.

25 In the drawings illustrating the invention, Figure I is a vertical section of a fire bowl equipped with my improved burner, the burner parts being shown in elevation. Fig. II is a central vertical section of the 30 fire bowl and burner. Fig. III is an inverted plan view of part of the burner base.

Referring more in detail to the parts: 1 designates the fire bowl of an ordinary heating stove with which the burner is to be 35 used. Seated on a flange 2 at the edge of the grate opening is a base 3 having a bowl-shaped central portion 4, provided with a central upturned drum 5. The part of the base within the drum is provided with ports 40 6 within which air is radiated to the burner to support combustion, and which are separated by a guide rib 6' having a central aperture 7 through which a supply pipe (presently described) is projected. Rising

45 from drum 5 is a collar 8, and rising from the collar, and preferably formed integral therewith, are standards 10, which are spaced to form openings 11 for the outlet of air admitted through ports 6.

50 Extending upwardly through the web aperture 7, and above the top of the collar standards 10, is an oil supply pipe 12, and threaded onto the upper end of said pipe and abutting against the tops of the standards 10 is a distributing plate 13 having an inclined top extending over and past the

base collar 8, and provided with an upturned edge flange 14, having slots 15 through which oil delivered onto the top of the distributor may flow.

60 On the under side of the distributor is a depending ring 16 which is so formed in relation to the under face of the distributor that oil escaping through the flange slots will by capillary attraction be held to the 65 under face of the distributor until it passes over the ring, from which it is adapted to drop into a trough 17 which is seated on the base shoulder 9 and surrounds the collar 8.

70 Supported on the top of the distributor and raised thereabove by legs 18 is a hood 19, the rim 20 of which is inclined downwardly and outwardly below the distributor ring 16 and to near the level of the top of the trough 17, the lower edge of the hood rim being provided with recesses 21 through which flame may escape to the exterior of the hood.

75 Mounted on the top of the hood, and raised thereabove, is a spreader 22 which extends almost to the sides of the fire bowl, so that flame from the burner is directed into direct contact with the bowl but may escape between same and the spreader 80 85 through an annular channel 23. In order to conserve heat from the burner, which necessarily becomes very hot on account of the contact of flame therewith, I prefer to place a number of fire brick 24 thereon.

90 In using the burner, presuming the parts to be constructed and assembled as described, with the fuel pipe 12 connected with a source of supply of suitable oil, when the burner is to be started a bit of paper, or the 95 like, (not shown) saturated with oil is placed in the annular cup 4 and ignited to heat the parts of the burner so that oil delivered thereover may be vaporized.

100 When the parts have become heated the supply pipe 12 is opened and oil rising therethrough is delivered over the top of the distributor; flows down the inclined surface and through the slots 15 in the flange over the curved edge of the distributor and down 105 the side of the ring 16 from which it drips into the trough 17. The trough 17 becomes quite hot while the burner is in operation so that the oil dropping thereonto is vaporized and rising, mixes with air admitted through 110 the interior of the drum 5 and delivered through the ports 11 between the top of the

collar and the distributer ring, so that a suitable fuel mixture is provided. The fuel vapor so generated is ignited and rises into contact with the spreader 22 where it is deflected against the sides of the fire bowl to apply the heat where it will be most effective.

Having thus described my invention, what I claim as new therein and desire to secure by Letters-Patent, is:—

- 10 1. In an oil burner, a base comprising a hollow drum having an inset collar forming a shoulder, and having spaced standards rising from the upper edge of the collar, a distributer supported on the standards, a trough located below the distributer, and a hood covering and spaced laterally from the distributer, for the purpose set forth.
- 15 2. In an oil burner, a hollow base comprising an annular cup and having spaced standards on its upper edge, a distributer supported on the standards, an annular trough supported by the base and adapted for receiving drippings from the distributer, and a hood supported on the distributer and spaced thereabove, the lower edge of the hood being recessed, substantially as set forth.
- 20 3. In an oil burner, the combination with a hollow base having laterally opening ports at its upper edge, a distributer mounted above the base, means for supplying oil to the top of the distributer, a trough surrounding the base adapted for receiving

drippings from the distributer, a hood supported above the distributer, and a spreader 35 carried by the hood.

4. An oil burner comprising a hollow base, having ports in its upper portion, a trough surrounding said base, a distributer, having an inclined upper surface and slotted edge 40 flange and having a ring on its under face overhanging said trough, and a hood inclosing said distributer.

5. The combination with a fire bowl having a grate opening, of a base member supported by the fire bowl and covering the grate opening, said base member comprising a hollow center drum having an apertured web and having an inset collar at its upper portion provided with spaced standards, a 50 supply pipe extending through the aperture in said web, a distributer threaded onto said supply pipe above the collar standards, an annular trough on said base collar below the distributer, a lower trough on said base, 55 a hood supported by the distributer and overhanging said lower trough, and a spreader supported on the hood and extending into proximity to the fire bowl, substantially as set forth. 60

In testimony whereof I affix my signature in presence of two witnesses.

WILLIAM J. LARIMER.
